UNITED STATES PATENT OFFICE.

WILLIAM H. SUTTON AND JAMES JOHN GIBSON, OF BRANTFORD, CANADA WEST.

IMPROVEMENT IN GRAIN-DRIERS.

Specification forming part of Letters Patent No. 40,130, dated September 29, 1863.

To all whom it may concern:

Be it known that we, WILLIAM H. SUTTON and JAMES J. GIBSON, of Brantford, in the county of Brant and Province of Canada, have invented a Combined Hot and Cold Air Mechanical Grain-Drier; and we do hereby declare that the following is a full, clear, and exact description of the same, reference being had to the accompanying drawings, making a part of this specification, in which—

Figure 1 is a plan or top view of our invention; Fig. 2, a longitudinal vertical section of the same, taken in the line $x\ x$, Fig. 1; Fig. 3, a transverse vertical section of the same, taken in the line $y\ y$, Fig. 1.

Similar letters of reference indicate corresponding parts in the several figures.

To enable those skilled in the art to fully understand and construct our invention, we will proceed to describe it.

A represents a kiln or hot air chamber of rectangular form, of any suitable dimensions and constructed in any proper way. Wood lined with metal would answer a good purpose. At the top of this kiln or hot-air chamber A there is a metal perforated plate, B, which is bent so as to form a series of concaves, a, the plate B being sustained by rods C, which are placed under the plate between the upper parts of the concaves a, as shown clearly in Fig. 3. The ends of the rods C are fitted in the ends of the kiln, and in each concave a there is placed a spiral conveyer, D. These conveyers are formed of a shaft, b, having a spiral flange, c, upon them, and they may be constructed by having the flange cast around a wrought-iron shaft, or by having wooden blades attached in a spiral line around a wooden shaft, or the flange and shaft may all be cast in one piece. These conveyers are made of such dimensions that they will fit snugly in the concaves, the edges of the flanges being in contact with the inner surfaces of the concaves. The ends of the shafts of the conveyers have their bearings in the ends of the kiln, and the upper ends of the concaves are on a level with the upper edges of the flanges of the conveyers, as shown in Fig. 3. The flanges c of the several shafts b have not all the same position, but are reversed alternately, as will be seen by referring to Fig. 1. This disposition or arrangement of the flanges enables us to rotate

the conveyers in opposite directions, as indicated by the arrows in Fig. 1, and still move the grain in the same directions in all the concaves, and thereby admit of the shafts b at one end having gears b', meshing directly into each other. If the flanges c were all in the same position on the shafts b, intermediate gears would be required in order to rotate the conveyers all in one direction and move the grain in the concaves accordingly. The perforations of the concaves a are sufficiently small to prevent grain passing through them, and are as close together as practicable to admit of the free passage of the heated air through them. On one end of the kiln A there is placed a hopper, E, which extends the whole width of the kiln, and is provided with an inclined bottom, d, having a number of holes, e, made in it, one over each concave a. The grain is spouted into this hopper, and passes from thence through the holes e into the concaves a, and is conveyed along in the concaves in the direction indicated by the arrows 1, motion being communicated to the conveyers from a driving-shaft, F, through the medium of a belt, f. The amount or volume of grain discharged into the concaves a may be regulated by means of slides, arranged to work over the holes e in the bottom of the hopper, and the speed of the driving-shaft F may be governed by having the driving-belt pass over cone-pulleys thereon. The grain is moved along in the concaves a, under the action of the conveyers, in thin sheets or strata, and the heated air from the kiln passes through the perforated concaves a at their bottoms and sides, and through the grain, drying the same in its passage along the concaves.

The kiln or hot-air chamber A may be heated direct by a stove placed within it, or a furnace may be inclosed within a hot-air chamber at any convenient distance from the kiln, the latter being supplied with heated air by means of suitable pipes. This latter arrangement would be attended with less risk from fire than the former plan. The dried grain passes from the concaves a into a chute, G, which leads into a cylindrical perforated tube, H, inclosed within a tight box, I, at one end of the kiln A. Within this tube H there is placed a spiral conveyer, J, the diameter of which may be rather greater than those of D,

The conveyer J is at right angles to the conveyers D, and J is rotated in the direction indicated by the arrow 2, and the grain is discharged through an opening, g, at one end of the bottom of the box I. The grain, while being thus moved in the perforated tube H, is subjected to a blast of cold air generated by the rotation of a fan in a case, K, at the discharge end of the box I, so that the blast will act against the grain as the latter is moved toward the jan. The box I being tight, the blast, having no other escape, passes through the perforated tube H, through the grain therein, and also through the chute G, as indicated by the arrows 3, the cold blast absorbing the heat from the grain and causing the same to be discharged from the box I in a cool state, so that it may be safely stowed away in bulk. In cases where the concaves *a* would be exposed to the weather—as, for instance, when on a floating elevator—the conveyers D may be covered, and the covering provided with a cowl at the top to admit of

the escape of the steam or vapor from the damp grain.

Having thus described our invention, what we claim as new, and desire to secure by Letters Patent, is—

1. The perforated metal plate B, bent so as to form a series of parallel concaves *a*, in combination with the spiral conveyers D and a kiln, A, all arranged to operate substantially as and for the purpose herein set forth.

2. The conveyer J, placed within the perforated tube H, fitted within a close or tight box, I, and communicating with the chute G, in combination with a fan or other blast-generating mechanism, all arranged substantially as shown, and, in connection with the grain-drying mechanism, to operate as and for the purpose set forth.

WILLIAM H. SUTTON.
JAMES JOHN GIBSON.
